UNITED STATES PATENT OFFICE.

CHARLES H. DAVIS, OF NEW YORK, N. Y.

DESIGN FOR AN ELECTRIC-RAILWAY CAR.

SPECIFICATION forming part of Design No. 28,073, dated December 21, 1897.

Application filed November 2, 1897. Serial No. 657,213. Term of patent 14 years.

To all whom it may concern:

Be it known that I, CHARLES H. DAVIS, of the city, county, and State of New York, have invented and produced a new and original 5 Design for Electric-Railway Cars, of which the following is a specification.

My design relates to the body of an electric-railway car.

In the accompanying drawings, Figure 1 is 10 a top view, Fig. 2 a side elevation, and Figs. 3 and 4 are elevations of opposite ends, of a car-body, exhibiting my design.

Similar letters of reference indicate like parts.

15 The car-body is approximately in elongated cubical shape. The top and bottom A B and the sides C D over a greater part of their length are planes. One end, E, of the body is

a plane at right angles to the sides. At the other end, F, of the body the top, bottom, and 20 each side are tapered and also curved inward, so that the extremities of said top, bottom, and sides appear to converge to the point G. This point of convergence is in the longitudinal central axis of the car-body. The top, 25 bottom, and sides of the car appear uniformly tapered at their ends and uniformly curved inward to converge at G.

I claim—

The design for an electric-railway car, substantially as shown and described.

CHARLES H. DAVIS.
